Term of patent 14 years

(Cl. D26—5)

FIG. 4

FIG. 5

FIG. 6

FIG. 1 is a front elevational view of a control console embodying my design;

FIG. 2 is an elevational view taken from one side thereof, the opposite side being a mirror image of the side shown;

FIG. 3 is a rear elevational view thereof;

FIG. 4 is a top plan view thereof;

FIG. 5 is a bottom plan view thereof; and

FIG. 6 is a cross sectional view taken on line 6-6 of FIG. 1.

The dominant features of my design reside in the portions in full lines.

What I-claim is:

The ornamental design for a control console, substantially as shown and described.
